UNITED STATES PATENT OFFICE.

HORACE T. HELMBOLD, OF PHILADELPHIA, PENNSYLVANIA.

BURGLAR-ALARM.

SPECIFICATION forming part of Letters Patent No. 310,421, dated January 6, 1885.

Application filed March 26, 1884. (Model.)

To all whom it may concern:

Be it known that I, HORACE T. HELMBOLD, a citizen of the United States, residing in the city and county of Philadelphia, State of Pennsylvania, have invented a new and useful Improvement in Burglar-Alarms, which improvement is fully set forth in the following specification and accompanying drawings, in which—

10 Figure 1 is a side elevation of a burglar-alarm embodying my invention. Fig. 2 is a longitudinal section thereof.

Similar letters of reference indicate corresponding parts in the several figures.

15 My invention consists of a burglar-alarm which is operated by dropping on the floor, &c., of an apartment within which it is suspended, the same having a telescopically-connected barrel and hammer or plunger and a cartridge or cap holder, the construction being such that the cartridge or cap is unfailingly discharged and the fire of the burning wad or paper thereof rapidly extinguished, the device being likewise simple, compact, 20 and inexpensive, as will be hereinafter fully set forth.

It further consists of means for preventing bursting of the barrel, as will be hereinafter fully set forth.

30 Referring to the drawings, A represents the body of the alarm, consisting of the tube or barrel *a* and the plunger *b*, fitted thereto telescopically, the lower end of the latter having a flange, *b'*, for preventing disconnection of the plunger and barrel, without, however, interfering with the sliding motions of said parts one within the other. The under side of the bottom of the plunger is provided with a spur or tooth, *B*, and the opposite or upper 35 end of the plunger is formed with an eye, *C*, which may be a hook or other device for the connection of a cord, *C'*, whereby the device may be suspended from a suitable part of a door, window, &c., to be protected.

40 To the lower end of the barrel *a* is attached a cartridge-holder, *D*, consisting of a tubular plug into which the cartridge or cap is inserted, the flange of the same resting on the upper edge of the plug. In the side of the plug 45 are openings or vents *e*, which communicate with the longitudinal bore of the plug and are in communication with openings or vents

d in the side of the barrel, at the bottom thereof. The plug is screw-threaded for connection with the threaded face on the interior of 50 the contiguous portion of the barrel, and the bottom of the plug is formed with a head, *e*, on which the alarm strikes when it is caused to fall or drop. The cartridge is applied to the holder *D* and the latter screwed to the barrel. The cord *C* is connected with the door, window, &c., it being noticed that the plunger and barrel are distended. When the door, &c., is opened, the cord is disengaged and the alarm drops on the floor or window-sill. The 55 plunger or hammer *b* then descends and its spur strikes the head of the cartridge, thus discharging the same and sounding the alarm. It will be seen that the wad or paper of the cartridge or cap or fulminate thereof is impelled against the bottom of the plug, and, traveling but a short distance, is rapidly extinguished, whereby fire is prevented from falling on the floor and igniting the latter or the carpet thereon, the smoke of course 60 escaping through the vents. Owing to the possibility of the cartridge-holder rotating during the discharge of the cartridge, and thereby partially closing the vents of the barrel, causing bursting of the barrel, the 65 vents of the barrel are made of greater diameter than that of the vents of the cartridge-holder, the vents of the two parts being in the same horizontal plane, so that should the holder rotate its vents move from the vents of 70 the barrel, which latter, being of the greater diameter, as has been stated, leave a larger amount of the vents of the holder uncovered than if both sets of vents were of the same diameter, thus providing vents of sufficient 75 size to permit the rapid escape of the gas and smoke of the discharged cartridge and avoiding bursting of the barrel, the bottom of the bore of the cartridge-holder being closed by the bottom of the plug, whereby the gas and 80 smoke are directed laterally through the vents, said face causing the extinguishment of the fire, &c., as has been stated.

Having thus described my invention, what I claim as new, and desire to secure by Letters Patent, is—

1. A burglar-alarm consisting of a barrel, a hammer fitted thereto telescopically, and a cartridge-holder, the hammer having its lower

end provided with a spur, the barrel having a vent near its bottom, and the holder having a vent which opens into the bore of the holder and communicates with the vent of the barrel, the bottom of the holder closing the bottom of the bore of said barrel and having a striking-head, substantially as and for the purpose set forth.

2. In a burglar-alarm, the barrel and car-

tridge-holder, having vents of different diameters or sizes, said holder being capable of rotation, and said vents located in the same horizontal plane, substantially as and for the purpose set forth.

HORACE T. HELMBOLD.
